UNITED STATES PATENT OFFICE.

LEWIS BENJAMIN DOMAN, OF EAST SYRACUSE, NEW YORK, ASSIGNOR TO THE
AMPHION PIANO PLAYER COMPANY, A CORPORATION OF NEW YORK.

NOTE-SHEET FOR SELF-PLAYING MUSICAL INSTRUMENTS.

1,169,741.

Specification of Letters Patent.

Patented Jan. 25, 1916.

Application filed September 17, 1915. Serial No. 51,168.

To all whom it may concern:

Be it known that I, LEWIS B. DOMAN, a citizen of the United States of America, and resident of East Syracuse, in the county of 5 Onondaga, in the State of New York, have invented new and useful Improvements in Note-Sheets for Self-Playing Musical Instruments, of which the following, taken in connection with the accompanying drawings, is a full, clear, and exact description.

This invention relates to certain improvements in note sheets for self-playing musical instruments and is adapted to be used more particularly in connection with a suitable selective apparatus not shown for playing one or more parts, as for example the solo part of a musical composition with greater force or emphasis than the remaining parts. These note sheets are usually 15 made of uniform or standard width capable of receiving a number of rows of note perforations corresponding to an eighty-eight note player, leaving a relatively narrow marginal space near one or both edges.

The main object is to provide the note sheet with a relatively smaller number of rows of selective perforations capable of automatically causing the individual notes of any one or more parts of a musical selection within the range of the player to be played with greater force or emphasis than the remaining parts.

The specific object is to enable these selective perforations to be placed in a relatively 35 narrow space on the ordinary note sheet of an eighty-eight note player without in any way interfering with the note perforations for the full range of the player.

Another object is to enable the same note 40 sheet with the selective perforations therein to be used for pianos, organs or similar self-playing instruments.

Other objects and uses will be brought out in the following description.

In the drawings—Figure 1 is a plan of a section of a note sheet showing several measures of note perforations of a musical selection and a portion of the system of selective apertures for causing one of the parts, as a 45 violin solo part, to be played with greater force than the remaining parts, the selective perforations being adapted for self-playing pianos, or reed instruments. Fig. 2 is a similar plan of a note sheet having the 50 same note perforations and a system of

slightly modified selective perforations adapted to be used more particularly with piano players.

As illustrated, the note sheet as —M— is provided with note perforations representing a musical composition in which one of the solo parts represented by perforations —a—b—c—d— is to be played with greater tone-volume or force than the remaining parts represented by the unmarked perforations, the solo part being adapted to be played in two adjacent octaves, but mostly in one octave. Under these conditions, I have shown the sheet as provided with but two parallel rows —1— and —2— of perforations, one row for each octave and running simultaneously with the perforations representing the solo part, a third line —3— being shown in which to place a similar row of perforations for another octave in case the solo part should extend into such additional octave, and it is evident that if the solo or other part or parts which are to be emphasized should run through the entire length of seven octaves of the player, it would necessitate the use of a corresponding number of rows of apertures, one for each octave, but no more.

Each octave, comprising twelve notes, is subdivided into four groups of three notes in each group.

The group notes are those which are discordant when played in any combinations to which they are susceptible, as for example—c, c#, d, as one group,—d#, e, f, as a second group,—f#, g, g#, as a third group, and—a, a#, and b, as a fourth group. The reason for thus grouping the discordant notes of each octave is that it would be very unusual for any musical composition to play any two notes of similar groups in the same or different octaves simultaneously, since the result would be irritatingly discordant.

The four different groups of notes are represented and controlled by a like number of separate rows—A, B, C, and D, of apertures or perforations in the note sheet running parallel with and adjacent to the several rows of octave perforations, each row of group perforations also representing and controlling the entire set of similar groups throughout all of the octaves of a player.

For convenience of further description,

the perforations in the lines —1—, —2—, —3—, and so on may be termed the "octave-selecting perforations", while those in the other four rows —A, B, C, and D, may be termed the "group-selecting perforations". These several rows of selective perforations are adapted to coöperate with suitable ducts of a tracker bar, not shown, for controlling the operation of suitable pneumatics also not shown. Portions at least of these selective perforations run simultaneously with the note perforations representing the solo or other part which is to be played with greatest force or emphasis, and for this purpose, the selective perforations are so placed upon the music sheet that their advance ends are in approximately the same transverse line as the corresponding ends of the note perforations representing the notes which are to be emphasized,—that is the advance ends of the selective perforations are adapted to register with their corresponding ducts at about the same time, or a little before, the corresponding ends of the note perforations register with their tracker ducts.

The position of the octave-selecting perforations in any of the several lines —1—, —2—, —3— and so on depends upon the octave or octaves in which the solo or other part to be emphasized is played, and consequently depends upon the position of the note perforation or perforations representing such solo or other part, so that if one or more measures of that part is played in one octave, the selective line of perforations representing that octave will run simultaneously with the note perforations in such measure or measures. If the solo part should run into another octave, the selective perforations for that octave would run simultaneously with the note perforations representing the notes in that octave, while the first line of octave-selecting perforations would terminate at about the beginning of the second line of octave-selecting perforations. It, therefore, follows that if the notes to be emphasized should run through the entire range of a seven octave player, it would require the use of seven rows of octave-selecting perforations, but no more. In like manner, the group-selecting perforations for any group of notes, either of which of that group is to be emphasized, begin at or slightly before the beginning of the note perforation in the sheet representing such note, and when the note sheet is used with reed or continuous tone instruments, the perforations run simultaneously and continuously with the note sheet aperture representing such note, as

shown in Fig. 1, or if the note sheet is to be used with pianos or similar instruments, it is only necessary to have a relatively short perforation occurring at the beginning of the note sheet aperture representing the note which is to be emphasized, as shown in Fig. 2. In other words, in the use of the note sheet in self-playing pipe organs, and other continuous tone instruments, the group perforations for any particular note which is to be emphasized are of substantially the same length as the perforations representing such notes.

In the use of this note sheet one or more of the group-selecting perforations must run simultaneously with one or more of the octave-selecting perforations in order that any note of a particular group may be played in the proper octave, although it is evident that the position of the group-selecting perforations may change from line to line according to the chance of notes as represented by the corresponding note perforations, while the octave-selecting perforations may run continuously in a single line so long as the notes to be played are within a single octave.

What I claim is:

1. A note-sheet having octave-selecting perforations and group-selecting perforations running simultaneously with certain note-perforations.

2. A note-sheet having note-perforations representing different parts of a musical composition, said sheet being provided with octave-selecting perforations and group-selecting perforations running in parallel lines simultaneously with the note-perforations representing one of said parts.

3. A note-sheet having note-perforations representing the parts of a musical composition, said sheet being provided with an octave-selecting aperture, and a coöperative group-selecting aperture occurring simultaneously with each other and with the advance end of one of the note-perforations.

4. A note-sheet having note-perforations representing different parts of a musical composition, said sheet being provided with octave-selecting apertures in different lengthwise lines, and coöperative group-selecting apertures also arranged in separate lengthwise lines and running simultaneously with portions of certain note-perforations.

In witness whereof I have hereunto set my hand this 7th day of September, 1915.

LEWIS BENJAMIN DOMAN.
